(57) **CLAIM**

The ornamental design for a step top flameless wax candle, as shown and described.

DESCRIPTION

FIG. 1 is a top and front perspective view of a step top flameless wax candle showing our new design;

FIG. 2 is a front elevational view thereof;

FIG. 3 is a rear elevational view thereof;

FIG. 4 is a left side elevational view thereof, the right side being a mirror image of that shown;

FIG. 5 is a top plan view thereof; and,

FIG. 6 is a bottom plan view thereof.

The broken-line disclosure in FIGS. 1 and 5 represents portions of the candle which form no part of the claimed design, and the broken-line disclosure in FIG. 6 represents an unclaimed boundary between the claimed design, shown in unbroken lines and provided with surface shading, and the unclaimed portions of the candle.
